UNITED STATES PATENT OFFICE.

CARL RUNQUIST, OF CHICAGO, ILLINOIS, ASSIGNOR OF ONE-HALF TO OSCAR G. ARFSTROM, OF BEEWYN, ILLINOIS.

PUMP.

1,221,602.

Specification of Letters Patent.

Patented Apr. 3, 1917.

Application filed January 28, 1916. Serial No. 74,730.

To all whom it may concern:

Be it known that I, CARL RUNQUIST, a citizen of the United States, residing at Chicago, in the county of Cook and State of Illinois, have invented certain new and useful Improvements in Pumps, of which the following is a specification.

My invention relates to pumps and more particularly to rotary fluid pumps or compressors.

One of the objects of my invention is to improve rotary pumps, to cheapen their cost and simplify their construction.

Other and further objects of my invention will become readily apparent, to persons skilled in the art, from a consideration of the following description when taken in conjunction with the drawings, wherein:

Figure 1 is a side elevation of a pump containing my invention.

Fig. 2 is an end elevation with the cover removed.

Fig. 3 is a longitudinal central section taken on line 3—3 of Fig. 2.

Fig. 4 is a perspective view of a fragment of part of the pump body.

In all the views the same reference characters are employed to indicate similar parts.

One of the salient objects of my invention is to construct a pump body and piston of such shape that they may readily be made by die casting, of suitable metal that will leave the surfaces as clear and smooth as if they had been tooled, so that the parts will be ready to be assembled as soon as they leave the dies.

In carrying my invention into effect the body part 5 is made of a single piece, and so shaped that it may be readily taken from the dies after being cast. It is provided with a base 6 and a concentric opening 7, providing a flange 8, of uniform width, between the opening and the outside surface of the casing or body part. The ports 9, which are made into the edge of the flange 8, on opposite sides, as at 9 and 9', taper upwardly into the inner surface defined by the flange 8. The rotary piston 10, provided with a shaft 11, is set eccentric to the cylinder or opening 7, so that the lower edge of the piston 10 makes intimate contact with the inner surface of the flange 8, as at 12. The piston 10 is uniformly round

and is provided with a plurality of radially extending slots 13, within which to contain blades 14, 15 and 16. These blades are thrown out by centrifugal effect until their outward edges bear against the inner surface of the flange 8.

A cap or cover 26, having a hub 17 carrying a bearing for the shaft 11, is secured to the body part 5 of the pump, by means of a plurality of screws 18. The intake pipe 19 and the discharge pipe 20 are secured in the cover 26 in front of the ports 9—9' as shown in dotted lines in Fig. 2.

Assuming that the piston 10 is rotating clockwise, air, or other fluid or liquid, will be taken in through the pipe 19 into the port 9 and drawn into the cylinder 7 by the effect of the receding blade 14, moving away from the port 9, into the cylinder space behind the blade. As the piston progresses the air or other fluid or liquid, will be discharged through the discharge pipe 20 in front of the approaching blade. The blade leaving the port 9 will continue to draw air into the cylinder space 7, behind it until the next succeeding blade has passed said port and the air that has previously been drawn in front of the former blade will be compressed as it is forced into the narrower passage as it approaches the discharge port.

The blades 14, 15 and 16 are of width equal to the thickness of the piston 10, so that there can be no leaks between the sides of the cylinder 7 and said blades or piston.

If the direction of rotation of the piston 10 be reversed, then the discharge pipe will become the intake pipe and the intake pipe will become the discharge pipe and the device will work with equal facility and advantage.

I have shown that in locating the ports 9 and 9' in the position as shown great advantage is secured and the efficiency of the device is greatly increased.

Having described my invention, what I claim is:

A rotary pump comprising a body part having a cylindrical opening with parallel end walls, a cylindrical vane-carrying rotor mounted eccentrically within the cylindrical opening and in peripheral contact with the cylinder wall on a line parallel with its axis, said casing having a port formed in the

peripheral wall of the cylinder at each side of the line of contact, each said port having a uniform axially extending cross section of semi-cylindrical formation at its lower portion merging into an upwardly extending wall substantially tangential to the peripheral wall of the rotor inclosing cylinder, and ducts leading axially through an end wall of the casing with their inner ends

registering with the semi-cylindrical portion of each port.

In testimony whereof I hereunto set my hand in the presence of two subscribing witnesses.

CARL RUNQUIST.
